6 Claims. (Cl. 257—256)

1

This invention relates to heat exchangers, and particularly to cooling apparatus, adapted for use in the manufacture of e. g. sulfuric acid, of the type in which the acid or other fluid to be cooled is flowed in the form of a ribbon or thick sheet between relatively closely arranged metallic heat transfer walls which are externally cooled by a cooling medium such as water.

In acid cooling apparatus of the kind to which this invention relates, it is important to maintain turbulence and to effect a complete breaking up or thorough mixture of all portions of the acid layer or ribbon being cooled in order to prevent the formation of a central core of relatively uncooled acid interiorly of the acid ribbon as the latter flows between the externally water-cooled side walls of the cooler. In order to provide for the foregoing, in prior apparatus, design has been such as to space the acid passage side walls rather close together, thus restricting the thickness of the acid layer or ribbon. Further, the area of heat transfer metal in contact with the acid is relatively fixed. These factors limit the capacity of a unit of given rectilinear dimensions.

The principal object of my invention is to increase the capacity of coolers of the type indicated and thereby decrease the number of units required for a given installation.

In accordance with this invention, I find that it is possible, in coolers of the kind mentioned, to substantially increase the area of heat transfer metal in contact with acid to be cooled and still maintain structural aspects which are needed to prevent core formation. By so doing, I am enabled to substantially increase the thickness of the acid layer and correspondingly increase the capacity of a cooler unit of given rectilinear dimensions.

The invention, its objects and advantages may be understood from the following description taken in connection with the accompanying drawings, in which

Fig. 1 is a partial front elevation, of the cooler unit of Figs. 1-4, taken on line 1—1 of Fig. 3;

Fig. 2, looking in the direction of the arrows of lines 2—2 of Figs. 3 and 4, is an elevation of a portion of the inside face of the rear side plate or casting of such cooler unit;

Fig. 3 is a horizontal section taken on lines 3—3 of Figs. 1, 2 and 4;

Fig. 4 is a vertical section taken on line 4—4 of Fig. 1;

Fig. 5 is a partial front elevation, of a modified cooler unit of Figs. 5—8, taken on line 5—5 of Fig. 7;

2

Fig. 6, looking in the direction of the arrows of lines 6—6 of Figs. 7 and 8, is an elevation of a portion of the inside face of the rear side plate or casting of such modified cooler unit;

Fig. 7 is a horizontal section taken on lines 7—7 of Figs. 5, 6 and 8;

Fig. 8 is a vertical section taken on line 8—8 of Fig. 5;

Figs. 9—16 inclusive are diagrammatic sketches hereafter discussed; and

Fig. 17 is an enlarged detail.

Referring to Figs. 1—4 of the drawing, representing a preferred embodiment of the invention, the improved cooler comprises vertically disposed front and rear side plates 10 and 11 preferably constructed of cast iron. Rear plate or casting 11, the inner or acid side of which is shown fragmentally in elevation in Fig. 2, comprises a side wall section 12 bounded on either vertical side edge by coplanar flanges 14 and 15. The upper horizontal edge of wall section 12 terminates in an upper half-header portion 16, and the lower horizontal edge of section 12 merges with lower half-header portion 17. The upper and lower header portions are each provided with vertical flanges 20 and 21 which are coplanar with side flanges 14 and 15. On each end of each half-header section is a semi-circular flange 23. Flanges 14, 15, 20, and 21 are drilled as at 25 to accommodate bolts by means of which front and rear plates 10 and 11 may be attached together to form a unitary structure which comprises spaced apart side wall sections, an upper horizontal header for inflow of acid to be cooled, and a lower outlet header for discharge of liquid from the unit. The flanges on the ends of the half-header inlet portions afford means for connecting the unit shown to other cooling units or to suitable acid inlet and outlet pipes.

In accordance with the invention, while side wall section 12 may be of any suitable form, preferably such section is made up of a series of horizontally disposed corrugations of relatively Z-shaped configuration, as shown on Fig. 4. A particular embodiment of the invention comprises wall section structure in which the terminal slopes of the wall section (as viewed in Fig. 4) adjacent opposite edges are substantially parallel. In the construction of a side wall, the angle A may be acute or obtuse and of any suitable angular value, but ordinarily lies within the range of 75—105 degrees and is preferably about 90 degrees. A corrugation leg length (distance B, Fig. 4) may vary substantially. However, in the preferred embodiments of the in-

vention, the particular values for angle A and leg length B are so chosen and correlated that the apex, e. g. at 27, of each convex surface of the inner side wall extends at least to and preferably thru a vertical a vertical plane passing thru the longitudinal axes of the upper and lower headers. This construction prevents the existence of a straight line downflow of an unbroken core of acid from the upper to the lower header.

A major feature of the invention which makes it possible to space the side wall sections relatively far apart, and thereby largely increase the capacity of the unit of given rectangular dimensions, and at the same time maintain the turbulence and effect complete breaking up and thorough mixture of all portions of the acid ribbon being cooled in order to prevent the formation of a central quiescent core of relatively uncooled acid, is the provision of inwardly projecting ribs on the inner face (the acid side) of wall section 12. Such ribs, when viewed in elevation as in Fig. 2, may take various forms in accordance with different modifications of the invention. Usually these ribs are cast integrally on the acid side of the wall section and the transverse surfaces thereof lie in planes which are disposed preferably at a right angle to the general vertical planes of side wall section 12.

In a preferred embodiment of the invention, Figs. 1-4, the ribs indicated generally by 30 appear in elevation (Fig. 2) as a series of corrugations of configuration broadly similar to that of the corrugated side wall portion 12 itself as shown in vertical section in Fig. 4. Each of ribs 30 is cast on the inner face (acid side) of wall section 12 so that the entire rib edge, remote from the inner face of wall section 12, lies in a vertical plane which passes thru the longitudinal axes of the upper and lower headers. This construction may be observed from Fig. 4 which shows that the innermost edges of all of ribs 30 and the inner faces of top and bottom flanges 20 and 21 and of side flanges 14 and 15 all lie in a common plane which includes the longitudinal axes of the upper and lower headers when the unit is assembled. Such arrangement and mode of casting of the ribs on the inner face of a side wall section 12 is characteristic of the better modifications of the invention.

Fig. 17, an enlarged elevational detail of Fig. 2, shows two adjacent ribs 33 and 34. The wave-like configuration of the ribs, when seen in elevation as in Figs. 2 and 17, may vary substantially. For example the angle C may be acute or obtuse, but in order to obtain good commercial results, angle C ordinarily lies within the range of 75-105 degrees. Preferably, angle C is approximately the same value as angle A of Fig. 4, and notably good acid turbulence is maintained when angles C and A are both approximately 90 degrees. Leg length, distance D Fig. 17, of a single wave or corrugation of a rib may likewise vary to a considerable extent. The spacing apart of the ribs, distance E, is subject to substantial variation. Preferably distance E is less than leg length D, and spacing apart of the ribs should be such as to provide a relatively narrow channel between two adjacent ribs. Further, if desired, in the more desirable forms of the invention when angle C is about 90°, spacing-apart distance E and leg length D may be so chosen and correlated that (1) straight line (linear) travel of an acid particle thru a channel is not substantially more than spacing apart distance E, and (2) the apex, e. g. 36 of rib 34,

Fig. 17, of a convex surface of a rib extends at least to and preferably just beyond a vertical plane which is disposed at a right angle to the vertical plane of wall section 12 and which passes thru the apices 38 and 39 of the adjacent convex surfaces of the adjacent rib 33, the vertical trace of such a plane being represented by the line F-F of Fig. 17. This arrangement prevents uninterrupted straight-line downflow of acid between two adjacent ribs, e. g. 33 and 34.

An important feature of all forms of the invention in which ribs 30 are wave-like or corrugated (when viewed in elevation as in Fig. 2), i. e. when the projection of the length of the rib on a plane parallel to the general planes of the wall sections is wave-like, corrugated or Z-shaped, and in which the side wall sections of the cooler are also wave-like or corrugated (as shown in the section of Fig. 4), is that the design of each rib 30 is such that the terminal slopes 41 and 42 (Fig. 2) of a given rib are relatively parallel. Thus, ribs 30 are formed so that an individual rib 30 is not made up of a plurality of complete wave lengths but comprises a plurality of complete wave lengths plus a half wave length, and because of this arrangement the courses of the terminal slopes of such rib are parallel rather than at right angles. The reason for this construction hereinafter appears.

Two major modifications of the embodiment of the invention illustrated in Figs. 1-4 are closely related to the foregoing feature. In the first modification, e. g. the front plate 10 is cast in a mold which is the same as the mold used for casting the rear plate 11 except that the mold employed for casting the front plate 10 is made so that the elevational configuration of the ribs 45 (Fig. 1) as cast on the inner side (acid side) of the front side wall section 13 are mirror patterns of the ribs on the inner side of the rear wall section 12, i. e. the projections of the ribs of one section on a plane parallel to the general planes of the wall sections are mirror patterns of similar projections of the ribs of the other section. In the second modification, both the front and rear plates 10 and 11 are cast in molds which are identical throughout. For convenience of discussion, these two modifications may be hereinafter referred to as "mirror patterns" and "identical patterns."

The selection of mirror or identical rib patterns is of importance in determining the structure of the cooler desired. As previously observed, the cooler unit is assembled by bolting a front and rear plate together at vertical edge flanges 14 and 15 and at horizontal upper and lower header flanges 20 and 21. The relation between mirror and identical rib patterns and the differences between heat exchange units which may be made by using a pair of mirror pattern rib side walls or a pair of identical pattern rib side walls may be understood from a consideration of Figs. 9-12.

Fig. 9 represents diagrammatically an elevation of the inside of a rear side wall section the same as side wall section 12 of Fig. 2. Fig. 10 indicates in elevation the inside of a casting which is the same in all other respects as the Fig. 9 casting except that in Fig. 10 the ribs 45 are mirror patterns of the ribs 30 of Fig. 9. It will be seen that when the casting of Fig. 10 is turned 70 up out of the plane of the paper and rotated 180° about edge 51, and the inside of the Fig. 10 casting is placed in abutting relation with the inside of the casting of Fig. 9, and so that edge 51 of Fig. 10 coincides with edge 52 of Fig. 9 and edge 54 of Fig. 10 coincides with edge 55 of Fig. 9, the re-

sulting unit construction is such that corresponding ribs 30 and 45 abut (except for the thickness of the gasket between the edge and top flanges) and are exactly coextensive. The unit appears in front elevation as shown in Fig. 12 in which the dotted line indicates a Z-shaped partition extending across the interior of the cooler unit and made up by the abutting and coextensive ribs 30 and 45. If the same casting of Fig. 10 were turned end-for-end it would appear as in Fig. 11. Further, if the inside of the casting in the position of Fig. 11 is then turned over 180° into abutting relation with the inside of the Fig. 9 casting, and so that edge 58 of Fig. 11 coincides with edge 60 of Fig. 9 and edge 57 of Fig. 11 coincides with edge 61 of Fig. 9, the resulting construction with respect to rib arrangement will be the same as before, i. e. as shown in Fig. 12 in which corresponding ribs on the opposite sides of the unit abut and form coextensive partitions across the cooler unit.

As was noted above, terminal slopes 41 and 42 of a rib 30 of Fig. 2 are parallel. This same relation is shown in Fig. 9, and it will be seen that although a rib 45 of Fig. 10 is a mirror pattern of a rib 30 of Fig. 9, the terminal slopes 64 and 65 of a Fig. 10 rib are also parallel. In accordance with the invention, it has been determined that when the interior ribs are wave-like or corrugated and when the side wall sections of the cooler are also wave-like or corrugated, the terminal portions of the ribs should be parallel so that when the front and rear wall sections are bolted together to form a unitary cooler, the waves or corrugations of the side wall sections "mesh" (as shown in Fig. 4) and form outer walls which are parallel even though of wave-like or corrugated formation. It will be appreciated that the foregoing discussion relative to Figs. 9-12 is descriptive of the assembly of the Figs. 1-4 modification which is made up in mirror pattern ribs.

Figs. 13-16 diagrammatically illustrate assembly and final construction of a unit made from two castings having identical rib patterns. Fig. 13 indicates in elevation the ribbed inside of a wall section the same as shown in Fig. 2. Fig. 14 represents in elevation the ribbed inside of a wall section which in all respects is identical with the wall section of Fig. 13. If the wall section of Fig. 14 is turned up out of the plane of the paper and rotated 180° so that the inner faces of both sections abut and so that edge 70 of Fig. 14 coincides with edge 71 of Fig. 13 and edge 73 of Fig. 14 coincides with edge 74 of Fig. 13 the resulting unit when viewed in front elevation will appear as in Fig. 16. From the latter, it will be noted that a rib 71 of Fig. 14 abuts a rib 78 of Fig. 13 at spaced intervals but that such abutment of corresponding ribs is in criss-cross preferably right-angled relation. If the wall section of Fig. 14 is turned end-for-end as shown in Fig. 15, and turned over 180° so that the inside of the wall section of Fig. 15 contacts the inside of the wall section of Fig. 13 and so that edge 80 of Fig. 15 coincides with edge 81 of Fig. 13 and edge 84 of Fig. 15 coincides with edge 85 of Fig. 13, the resulting cooler unit is the same as shown in Fig. 16. It is noted that the terminal portions of the rib 78 of Fig. 13 are parallel, and that the same is true with respect to the rib 71 of Fig. 14. This parallelism of rib terminal portions provides a construction, in the case of identical patterns as well as in the case of mirror patterns, by which it is possible to insure the meshing relation of the corrugations of the outside wall sections.

Referring again to Figs. 1-4, it will be noted that the upper end of each channel between two adjacent ribs 30 opens into the upper header, and the lower end of such channel discharges into the lower header. In this embodiment of the invention, the coextensive relationship of corresponding ribs on the rear and front wall sections 13 and 12 is illustrated particularly in the section of Fig. 3 which shows that corresponding rear and front ribs form unbroken partitions extending transversely of the cooler unit, and that any two adjacent partitions form a channel 90 which in horizontal section is elongated transversely of the cooler unit. Such channel provides for a ribbon or stream of acid to be cooled having a horizontal cross-sectional area corresponding with the horizontal cross-sectional area of the channel.

As more clearly shown in the enlarged detail of Fig. 17, the ribs are constructed preferably to provide a plurality of sharply inclined reversely extending surfaces against which the acid in the channel 90 impinges. After the acid flows downwardly in one portion 92 of a channel 90, an abrupt change in the direction of flow produced by the sharp concave turn of the rib 33 causes the relatively sluggish skins of acid particles, formerly in contact with opposing faces of the ribs, and the faster moving central core of acid, which was not in direct contact with the surface of either rib, to be vigorously churned up and thoroughly mixed. As the acid flows to the end of the next lower and oppositely inclined portion 97 of channel 90, a similar though oppositely disposed turbulence and mixing of the acid is effected. It will be observed that the ribs are provided with a plurality of convex surfaces e. g. 36 (Fig. 17) and a plurality of concave surfaces 100 connected by inclined surfaces e. g. 101. Thus, the acid between two adjacent ribs is projected successively across each passage 90 from one rib to the adjacent rib. It will be understood that the shorter the lineal length of the inclined surfaces, the greater will be the turbulence of the acid flowing between two adjacent ribs, the maximum effect being obtained when the linear straight line travel lengths of inclined portions 92 and 97 are not substantially longer than the width of each channel 90. However, as will hereafter more fully appear, the invention is such as to greatly increase the metal heat transfer surface in contact with acid, and accordingly permits not only a substantial increase of the distance between side walls 12 and 13 (Fig. 4) but also a reduction in the total number of corrugations in a side wall section 12. Such reduction entails a lengthening of a leg length B (Fig. 4), but does afford substantial manufacturing conveniences. Because of the multiple turbulences effected by the combined action of ribs 30 and corrugated side walls 12 and 13, according to this invention, short leg lengths, e. g. distances B and D of Figs. 4 and 17, are not required.

The ribs 30 are formed and spaced so that the apex of an inner convex surface 36 of one rib projects at least to and preferably thru a vertical plane F as mentioned in connection with Fig. 17. This construction prevents an uninterrupted vertical descent of any liquid directly from the upper header to the lower header, and also prevents the passage of liquid particles between adjacent ribs without causing such particles to be repeatedly projected from contact with one rib to contact with another.

Referring to Fig. 2, it will be observed that the wave-like course or undulation of a ribbon of acid flowing downwardly between two adjacent ribs 30 lies in a general plane disclosed at right angles to the rear and front side wall sections 12 and 13 of the cooler unit. It will be noted also that, in the particular embodiments of Figs. 1-4, with respect to leg lengths and angularities, the wave-like configuration of the rear and front walls 12 and 13 (Fig. 4) is similar to or approximately the same as the configuration of a rib 30 (Fig. 2). Accordingly, it will be seen from a consideration of Fig. 4, that corrugated side walls 12 and 13 cause downflowing acid to take the form of undulations similar to the undulations effected by ribs 30. However, since the general planes of side walls 12 and 13 are at right angles to ribs 30, it will be understood that undulations effected by the side walls lie in a general plane parallel to the rear and front walls and are disposed at right angles to the undulations caused by ribs 30. That is, ribs 30 effect one set of downflowing acid undulations while side walls 12 and 13 cause another set of undulations, the latter being at right angles to the former. Accordingly, it will be appreciated that the preferred construction of the invention, comprising wave-like ribs and wave-like side wall sections, is such that the turbulence, core breaking, and acid mixing described above specifically in connection with the undulations formed by the configuration and spacing of ribs 30 are substantially duplicated by the configuration and spacing of side walls 12 and 13. Further, since the two sets of wave-like courses or undulations are disposed at an angular relation to each other, the particles of downflowing acid are being continuously transferred from one set of undulations to another, and the invention provides constructions which multiply acid turbulence and mixing severalfold. It will be apparent, therefore, that the wave-like constructions of the ribs 30 and of the side walls 12 and 13 together repeatedly cause vigorous breaking up and reversal of all parts of the fluid stream being cooled and effect thorough admixture of all increments of acid. Since direction reversals of acid flow follow each other in rapid succession, there is no opportunity for coring of the acid, and particles of each acid ribbon are repeatedly and rapidly brought into direct contact with metal cooling surfaces.

The principal function of ribs 30 is to largely increase the amount of metal heat-conducting surfaces within a minimum space. As will be observed from Fig. 3, the inwardly projecting ribs greatly multiply the extent of metal heat-conducting surface in contact with acid as compared with constructions which comprise only side walls such as 12 and 13 and do not contain the inwardly projecting ribs. In cooler units of the latter type which do not include inwardly projecting ribs, in order to provide reasonably satisfactory turbulence, core breaking, and acid mixing as the acid flows down between the outer cooler walls, it is necessary that the side walls be positioned close together. This limits the total area of the acid passageway between the upper header and the interior of the cooler unit as defined by the closely spaced side walls, and correspondingly limits the capacity of a unit of given rectangular dimensions. In accordance with this invention, provision of the ribs 30 projecting into the body of acid in the cooler unit affords such a great increase of metal cooling surface in contact with acid as to make it pos-

sible, depending upon the conductivity of the material of construction, to space apart the side walls distances equal to two to twenty times the spacing permissible in similar but non-ribbed cooler units. The combined result of the use of the inwardly projecting ribs and the much farther apart spacing of the side walls is that the total area of the several channels 90 as shown on Fig. 3 is greatly increased as compared with the total area of the passageway between the upper header and the interior of the cooler in constructions in which the inwardly projecting ribs are not provided and in which the absence of such ribs requires close spacing of side wall sections such as 12 and 13. On the basis of given rectangular dimensions (i. e. rectangular dimensions of the elevations of Figs. 1 and 2), again depending upon the conductivity of the material of construction, the invention affords the advantage that capacity of a cooler unit may be increased from two to ten times the capacity of a similar cooler unit not provided with the inwardly projecting ribs.

The cooling of the acid passing downwardly within the unit may be effected by a sheet of water or other cooling fluid flowing down over the outer surface of the apparatus. The configuration of the corrugations forming the side walls is such that the cooling liquid flows along the walls in a thin, continuously unbroken film. On account of the angularity of the turns and the comparatively short inclined connecting portions constituting the side walls, the liquid adheres to the surface of the walls and does not tend to drip off the edges at the convex ridges formed by two inclined intersecting surfaces, thus cutting off the flow of liquid in the concave portions of the wall surface.

Cooling liquid may be supplied in any suitable manner as, for instance, from conduits 110 arranged alongside the upper acid inlet header. Conduits 110 may be supported, e. g. by brackets (not shown) or by any suitable means associated with the cooler unit. The water in the conduits 110 may be under some pressure and sprayed over the upper outer edge of each side wall through a series of perforations 111 in the sides of the conduits immediately adjacent the outer surface of the cooler. Such perforations are spaced closely, and act to spray water onto the sides of the cooler in such a manner that the cooling liquid forms a substantially even film which flows down over the outer surfaces of the cooler in the form of a thin film.

In the cooler of the modification of Figs. 13-16, i. e. in which apparatus corresponding ribs on opposed side walls are identical patterns, the set of acid channels formed by the inwardly projecting ribs on the front casting of the unit criss-cross and are disposed in right angular relationship to the set of acid channels formed by the inwardly projecting ribs on the rear casting of the unit. In use, the cooler of the Figs. 13-16 modification functions generally similarly to the unit of Figs. 1-4. However, in the embodiment of Figs. 13-16 it will be understood that, except where inwardly projecting corresponding ribs of the front and rear casting actually abut (in angular criss-cross relation), the set of acid channels formed by the ribs on the front casting of the unit are in angularly disposed but open communication with the set of acid channels formed by the ribs of the rear casting of the unit. Thus, during the downflow of acid thru the unit, in addition to the undulations and resultant acid

mixing caused by the corrugations of the outer walls 12 and 13, the inwardly projecting wave-like ribs on the rear casting, and the inwardly projecting but criss-cross related ribs on the front casting, there is a constant interflow of acid particles from the acid channels of one set of ribs to the acid channels of the other set of ribs. It will be appreciated that this crossflow of acid particles from one set of channels on one half of the unit to a criss-cross related set of channels on the other half of the unit provides a still greater degree of turbulence, core breaking and acid mixing than described above in connection with Figs. 1-4.

Figs. 5-8 represent a further modification of my improved cooler. The overall structure of this modification is similar to that of the preferred embodiment shown in Figs. 1-4, except for the arrangement of the internal ribs and the passages defined thereby. Included in this modification are a plurality of equally spaced, parallel, vertical ribs 115 cast integrally at right angles to the inner surface of rear side wall section 117, and a plurality of similar ribs 118 cast on the inner surface of front side wall section 119. Each of the ribs 115 and 118 extends in length from the top header 16 to bottom header 17. As seen in Fig. 8, in side elevation ribs 115 have the general configuration of the rear side wall 117, and ribs 118 bear similar relation to front side wall section 119. If desired, ribs 115 and 118 may be cast on the respective wall sections so that the inner edge of each rib is a straight line which lies in a vertical plane passing thru the longitudinal axes of headers 16 and 17.

When the front and rear sections 119 and 117 of Fig. 8 are bolted together to form a unitary structure, corresponding ribs on the opposing side walls are co-extensive, substantially abut each other, and form vertical partitions across the inside of the unit. The space bounded by two adjacent ribs 115 on one side wall, the two oppositely adjacent ribs 118 on the other side wall, and the two side walls form between the side walls a restricted tortuous inner passage which communicates with top and bottom headers 16 and 17.

Since in the modification shown in Figs. 5 to 8, the ribs are vertical rather than zig-zag as in the embodiment of Figs. 1 to 4, the turbulence of the acid in the cooler of Figs. 5-8 is brought about by the corrugations of the side walls. Consequently, in order to prevent the vertical descent of a quiescent central core of acid without contacting the side walls 117 and 119, the corrugations should be chosen and constructed so that the apex (e. g. 125) of each inner convex surface of both side walls extends at least to and preferably thru a vertical plane passing thru the longitudinal axes of headers 16 and 17. The cooler unit of Figs. 5-8 may be assembled from half-sections cast from identical molds.

Although the coolers of the invention have been described as being constructed of cast iron, other metals such as stainless steel, aluminum, etc. may be employed.

I claim:

1. Heat exchange apparatus comprising front and rear side plates each having a side wall section, a header portion adjacent the top and the bottom of each wall section, means connecting said plates to form a unitary structure having a top and a bottom header, said side wall sections being horizontally and relatively parallelly corrugated and being spaced apart from each other, the terminal slopes of the corrugations of each

wall section adjacent said headers being substantially parallel, a plurality of inwardly projecting ribs attached to the inner face of each wall section, the transverse surfaces of said ribs lying in planes at an angle to a plane passing through the longitudinal axes of said headers, said ribs having a wave-like projection on a plane passing through the longitudinal axes of said headers, the terminal slopes of each of said inner ribs adjacent said headers being substantially parallel, said ribs of both wall sections being formed so that at least a plurality of portions of the inner edges of corresponding ribs on opposed sections substantially abut, thereby to provide between said wall sections a plurality of restricted fluid passageways connecting said headers.

2. Heat exchange apparatus comprising front and rear side plates each having a side wall section, a header portion adjacent the top and the bottom of each wall section, means connecting said plates to form a unitary structure having a top and a bottom header, said side wall sections being horizontally and relatively parallelly corrugated and being spaced apart from each other, the terminal slopes of the corrugations of each wall section adjacent said headers being substantially parallel, a plurality of inwardly projecting ribs attached to the inner face of each wall section, the transverse surfaces of said ribs lying in planes at an angle to a plane passing thru the longitudinal axes of said headers, said ribs having a projection—on a plane passing thru the longitudinal axes of said headers—of substantially the same configuration as a vertical section of a side wall section, the terminal slopes of each of said inner ribs adjacent said headers being substantially parallel, said ribs of both wall sections being formed so that at least a plurality of portions of the inner edges of corresponding ribs on opposed sections substantially abut, thereby to provide between said wall sections a plurality of restricted fluid passageways connecting said headers.

3. Heat exchange apparatus comprising front and rear side plates each having a side wall section, a header portion adjacent the top and the bottom of each wall section, means connecting said plates to form a unitary structure having a top and a bottom header, said side wall sections being substantially Z-shaped in vertical section and being spaced apart from each other, the terminal slopes of each wall section adjacent said headers being substantially parallel, a plurality of inwardly projecting ribs attached to the inner face of each wall section, the transverse surfaces of said ribs lying in planes at an angle to a plane passing through the longitudinal axes of said headers, said ribs having a substantially Z-shaped projection on a plane passing through the longitudinal axes of said headers, the terminal slopes of each of said inner ribs adjacent said headers being substantially parallel, said ribs of both wall sections being formed so that at least a plurality of portions of the inner edges of corresponding ribs on opposed sections substantially abut, thereby to provide between said wall sections a plurality of restricted fluid passageways connecting said headers.

4. Heat exchange apparatus comprising front and rear side plates each having a side wall section, a header portion adjacent the top and the bottom of each wall section, means connecting said plates to form a unitary structure having a top and a bottom header, said side wall sections being substantially Z-shaped in vertical section

and being spaced apart from each other, the terminal slopes of each wall section adjacent said headers being substantially parallel, a plurality of inwardly projecting vertically disposed ribs attached to the inner face of each wall section, the transverse surfaces of said ribs lying in planes at a right angle to a plane passing through the longitudinal axes of said headers, said ribs having a substantially Z-shaped projection on a plane passing through the longitudinal axes of said headers, the terminal slopes of each of said inner ribs adjacent said headers being substantially parallel, said ribs of both wall sections being formed so that at least a plurality of portions of the inner edges of corresponding ribs on opposed sections substantially abut, thereby to provide between said wall sections a plurality of restricted fluid passageways connecting said headers.

5. Heat exchange apparatus comprising front and rear side plates each having a side wall section, a header portion adjacent the top and the bottom of each wall section, means connecting said plates to form a unitary structure having a top and a bottom header, said side wall sections being horizontally and relatively parallelly corrugated and being spaced apart from each other, the terminal slopes of the corrugations of each wall section adjacent said headers being substantially parallel, a plurality of inwardly projecting ribs attached to the inner face of each wall section, the transverse surfaces of said ribs lying in planes at an angle to a plane passing thru the longitudinal axes of said headers, said ribs having a projection—on a plane passing thru the longitudinal axes of said headers—of substantially the same configuration as a vertical section of a side wall section, the terminal slopes of each of said inner ribs adjacent said headers being substantially parallel, said ribs of both wall sections being formed so that at least a plurality of portions of the inner edges of the ribs on one section substantially abut, in criss-cross relation, portions of the inner edges of the ribs of the other section, thereby to provide between said wall sections a plurality of restricted fluid passageways

connecting said headers, said wall sections being of substantially identical construction.

6. Heat exchange apparatus comprising front and rear side plates each having a side wall section, a header portion adjacent the top and the bottom of each wall section, means connecting said plates to form a unitary structure having a top and a bottom header, said side wall sections being horizontally and relatively parallelly corrugated and being spaced apart from each other, the terminal slopes of the corrugations of each wall section adjacent said headers being substantially parallel, a plurality of inwardly projecting ribs attached to the inner face of each wall section, the transverse surfaces of said ribs lying in planes at an angle to a plane passing thru the longitudinal axes of said headers, said ribs having a projection—on a plane passing thru the longitudinal axes of said headers—of substantially the same configuration as a vertical section of a side wall section, the terminal slopes of each of said inner ribs adjacent said headers being substantially parallel, said ribs of both wall sections being formed so that the inner edges of corresponding ribs on opposed sections substantially abut throughout their length, thereby to provide between said wall sections a plurality of restricted fluid passageways connecting said headers.

EDWIN B. LOPKER.
